US00D642330S

(12) **United States Design Patent**
Turner

(10) **Patent No.:** **US D642,330 S**
(45) **Date of Patent:** ** *Jul. 26, 2011

(54) **DELIVERY DEVICE**

(76) Inventor: **Jeffrey Turner**, San Clemente, CA (US)

(*) Notice: This patent is subject to a terminal disclaimer.

(**) Term: **14 Years**

(21) Appl. No.: **29/368,119**

(22) Filed: **Aug. 18, 2010**

Related U.S. Application Data

(63) Continuation-in-part of application No. 29/346,050, filed on Oct. 26, 2009, now Pat. No. Des. 624,238.

(51) **LOC (9) Cl.** **27-01**

(52) **U.S. Cl.** **D27/101; D24/133**

(58) **Field of Classification Search** D27/100, D27/101, 170, 183; D24/108, 110, 112, D24/113, 114, 133; 131/270-273, 360, 194; 606/108

See application file for complete search history.

(57) **CLAIM**

The ornamental design for a delivery device, as shown and described.

DESCRIPTION

FIG. 1 is a top, rear, left side perspective view of the delivery device;

FIG. 2 is a rear view of the delivery device of FIG. 1;
FIG. 3 is a left side view of the delivery device of FIG. 1, the right side view is a mirror image thereof; and,
FIG. 4 is a top plan view of the delivery device of FIG. 1.
The outermost broken line shown in the rear view in FIGS. 1 and 2 represents the bounds of the claimed design while all other broken lines are directed to environment and are for illustrative purposes only. The broken lines form no part of the claimed design.

1 Claim, 2 Drawing Sheets
